UNITED STATES PATENT OFFICE

ELMER E. HAUER, OF SPRINGFIELD, OHIO, ASSIGNOR TO THE LAGONDA MANUFACTURING COMPANY, OF SPRINGFIELD, OHIO, A CORPORATION OF OHIO.

TURBINE.

1,102,744.

Specification of Letters Patent.

Patented July 7, 1914.

Application filed December 22, 1911. Serial No. 667,378.

To all whom it may concern:

Be it known that I, ELMER E. HAUER, a citizen of the United States, residing at Springfield, in the county of Clark and 5 State of Ohio, have invented certain new and useful Improvements in Turbines, of which the following is a specification, reference being had therein to the accompanying drawings.

10 My invention relates to turbines and more particularly to a turbine for driving boiler tube cleaners adapted to follow the cleaner into a tube, although it may be used for other purposes.

15 The object of my invention is to provide an improved turbine of this class simple and compact in construction, of few parts easily assembled and taken apart.

With these and other objects in view my 20 invention consists of the constructions and combinations hereinafter described and set forth in the claims.

In the accompanying drawings which 25 form a part of this specification Figure 1 is a longitudinal section of a motor embodying my invention and shows a tube cleaner attached thereto. Fig. 2 is a section of a portion of the motor showing the front bearing with modified means for lubricating said 30 bearing and this view further shows a drill head secured to the motor by a universal joint, and Fig. 3 is a cross-section taken on the line 3-3 of Fig. 1.

Like numerals represent the same parts in 35 the several views.

In the drawings 1 represents a casing having an integral head 2 at its front end and a removable head 3 at its rear end having a screw-threaded opening 4 to attach a 40 supply conduit. Said head 3 projects forwardly within the casing 1 and is screw-threaded thereto at 5. A disk or partition 6 is preferably formed integrally with the head 3 and is provided with a rearwardly 45 extending portion 7 to form a bearing for a shaft 8 and I preferably provide a removable bushing 9 for said bearing. A cap 9^a closes the rear end of the bearing.

A hollow shaft or rotating member 10 is 50 journaled in an opening through the front head 2, a removable bushing 10^a being preferably provided as a bearing for same. Said shaft or member 10 projects rearwardly in the casing and a disk or partition 55 11 is screw-threaded within the shaft or

member 10 to carry the shaft 8. Said shaft may be fixed to said disk in any suitable manner but I have shown the same as made integral therewith. The turbine wheel 12 is mounted on the shaft 8 and is preferably provided with a central hardened portion 13 screw-threaded therein. It may be secured to the shaft in any proper way but I have shown the same keyed to the shaft by a key 14 against a shoulder on the shaft. 65 The motive agent being introduced through the opening 4 passes through the usual inclined ports 15 in the partition 6 into the bucket 16 of the wheel 12 and is discharged therefrom through the opening 17 in the 70 partition 11 and thence through the openings 18.

In Fig. 1 I have shown a cleaner head the base 19 of which is screw-threaded to the end of the shaft 10, said base being provided with openings 20 affording additional discharge for the motive agent; and in Fig. 2 I have shown a drill head with a universal coupling, the member 21 of which is screw-threaded to the shaft and provided with the 75 openings 22 affording additional discharge.

It will be seen the hollow shaft 10 extends rearwardly past the ports 15 in the partition 6 and incloses the wheel 12; and the shaft 8 is secured to the shaft 10 by the 80 partition 11 so that all said parts rotate with the wheel and are carried by front and rear bearings as described.

The bushing 10^a is provided with a flange 23 which extends between the front head 2 and a shoulder on the shaft 10 to take the forward thrust and I preferably provide a wearing ring 24 between said flange and shoulder; and the bushing 9 is provided with a flange 25 to take the rearward thrust. 95

An opening 26 through the cap 9^a registers with a conduit 27 in the shaft 8 and admits the motive agent to the rear bearing for the purpose of lubrication; and a screw-threaded grease cup or reservoir 28 in the 100 head 2 is provided with a screw plug 29 to force the lubricant through the openings 30 to the front bearing. In Fig. 2 I have shown means for lubricating the front bearing by admitting the motive agent to said 105 bearing through the openings 31.

Having thus described my invention I claim:

1. In a turbine, a wheel having a hollow shaft forming a shroud for said wheel and 110

- projecting therefrom to carry the discharge from said wheel.
2. In a turbine, a casing having an integral front head with an opening therethrough, a bush bearing in said opening, a wheel having a hollow shaft journaled in and projecting through said bearing with openings to discharge the motive agent in front of said bearing from the wheel.
- 10 3. In a turbine, a casing having a front head with an opening therethrough, a bush bearing in said opening; a wheel having a hollow shaft journaled in and projecting through said bearing with openings to discharge the motive agent in front of said head from the wheel and a thrust bearing between said head and a shoulder on said shaft.
- 20 4. In a turbine, a casing having a front head, a wheel having a hollow shaft projecting forwardly from said wheel through an opening in said head and journaled therein, a tool secured to said shaft having openings for the discharge of the motive agent from the wheel.
- 25 5. In a turbine, a casing having an integral front head and a removable rear head, a wheel having a forwardly and rearwardly extending shaft, front and rear bearings for said shaft, the forwardly projecting shaft being hollow and having openings to discharge the motive agent from the wheel in front of said front head and means to lubricate said front and rear bearings.
- 30 6. In a turbine, a casing having an integral front head and a removable rear head, a wheel having a hollow shaft journaled in and projecting through said bearing with openings to discharge the motive agent from the wheel in front of the front head and means to lubricate said journal and thrust bearings.
- 40 7. In a turbine, a wheel, a forwardly projecting hollow shaft, a rearwardly extending solid shaft, and a ported partition to secure said shafts together, said hollow shaft forming a shroud for said wheel.
- 45 8. In a turbine, a casing, a stationary ported partition, a wheel having a hollow shaft forming a shroud for said wheel and ported partition, said shaft projecting forwardly to discharge the motive agent from said wheel.
- 50 9. In a turbine, a casing having a front head with an opening therethrough, a stationary ported partition, a wheel having a hollow shaft forming a shroud for said wheel and partition and projecting forwardly through and being journaled in the opening in said head and adapted to discharge the motive agent from the wheel in front of said head.
- 55 In testimony whereof I have hereunto affixed my signature in the presence of two witnesses.
- ELMER E. HAUER.
- Witnesses:
- GROVER ILGEN,
OLIVER H. HAUSE.
